DESIGN FOR AN AUTOMOBILE INSTRUMENT PANEL

Arthur A. Ross, Detroit, Mich., assignor to General Motors Corporation, Detroit, Mich., a corporation of Delaware

Application February 18, 1948, Serial No. 144,582

Term of patent 3½ years

(Cl. D52—1)

To all whom it may concern:

Be it known that I, Arthur A. Ross, a citizen of the United States, residing at Detroit, in the county of Wayne and State of Michigan, have invented a new, original, and ornamental Design for an Automobile Instrument Panel, of which the following is a specification, reference being had to the accompanying drawing, forming part thereof.

The figure is a perspective view of an automobile instrument panel, showing my new design.

The characteristic features of my design reside in the portion shown in solid lines.

I claim:

The ornamental design for an automobile instrument panel, as shown and described.

ARTHUR A. ROSS.
